SKY LINE LOGGING CARRIAGE

James L. Yelton, Bellingham, Wash.

Application March 15, 1948, Serial No. 14,971

18 Claims. (Cl. 212—122)

1

This invention relates to a sky line logging carriage adapted for use in picking up and transporting logs but the same can be used for other purposes wherein a carriage supported for movement on a track cable is used for picking up and transporting loads.

An object of this invention is to provide load pick up and transporting devices in which the load is picked up and transported clear of the ground rather than being dragged along the ground, as is frequently done in logging.

In logging operations it is common practice to employ an overhead track cable or sky line having a carriage movable thereon to bring the logs from the location where they are felled to a central loading point, this being done by lifting one end portion of the log and dragging the other end portion thereof along the ground. By the use of such apparatus many small trees, which it is desirable to save in the interest of re-forestation and forest conservation, are destroyed. It is an object of this invention to provide logging equipment which will make it possible to conserve and save these small trees.

Another object is to provide an efficient carriage which will simplify the work of picking up logs and transporting them clear of the ground.

A further object is to provide a carriage having thereon means operated by movement of the carriage along its track cable for compressing fluid and further having thereon means for utilizing such compressed fluid for operating cable clamp means and drum brake means.

Another object is to provide a carriage having novel control means responsive to movement of the carriage along a track cable and responsive to stopping of the carriage on the track cable and operable to control the application and release and holding of cable clamp means and drum brake or locking means.

Another object is to provide a carriage having control means which combines cable operation and automatic operation and to provide in said control means air coupling means of novel form which obviates interference between the cable operated control means and the automatic control means.

Other objects of the invention will be apparent from the following description taken in connection with the accompanying drawings.

In the drawings

Figure 1 is a perspective view showing a general arrangement of rigging and the use of this sky line carriage.

Fig. 2 is a side elevation of the sky line carriage embodying the invention.

2

Fig. 3 is a plan view of the carriage shown in Fig. 2.

Fig. 4 is a section taken on line 4—4 of Fig. 2.

Fig. 5 is a diagram of the hydraulic cable clamp and brake means and control means therefor.

Fig. 6 is a detached sectional view of a four way valve used in the hydraulic means.

Fig. 7 is a sectional view of a hydraulically operated governor device which can be used in the control means in place of a flyball governor.

Referring more particularly to the drawings reference numeral 10 designates the carriage in its entirety. The frame of this carriage is composed of two longitudinal channels 11 and 12 on the top and near the center of which are secured two cross channels 13 and 14 preferably welded to channels 11 and 12. Welded to and projecting downward from the ends of channels 13 and 14 are two side frame members 15 and 16. Near the right end of channels 11 and 12, Figs. 2 and 3, are journal bearings 17 in which rotates shaft 18 to which is secured sheave 19. Near the end of channels 11 and 12 shown at the left in Figs. 2 and 3 are mounted journal bearings 20 in which is rotatively mounted a shaft 21 to the center of which is secured a sheave 22. To one end of shaft 21 is keyed a bevel gear 23. Meshing with bevel gear 23 is a bevel gear 24 of a governor which will be described more in detail later. To the opposite end of shaft 21 is secured an eccentric 25 for operating an oil pump which will also be described more in detail later.

Near the center of side frames 15 and 16 is secured a shaft 26 on which is rotatively mounted a unit drum represented in its entirety by reference numeral 27. Unit drum 27 is composed of three drum sections 28, 29 and 30. On drum section 28 is wound a main line cable and on drum section 29 is wound a pick-up cable and on drum section 30 is wound a haul-back cable. These cables are hereinafter described in connection with Fig. 1.

Drum section 28, see Fig. 4, is provided with an outer flange 31 and is separated from drum section 29 by the common flange 32. Drum section 30 is provided with an outer flange 33 and is separated from drum 29 by a common flange 34. All of the flanges 31—32—33—34 extend inwardly to where they unite with a common cylindrical section 35 the outer ends of which are provided with hubs 36 into which are pressed sleeves 37 which rotate freely on the shaft 26.

From the inner peripheral face of drum 30 projects a flange 35a. 38 is a brake drum which is provided with a brake surface 39, an inwardly projecting flange 40, and outwardly projecting

lugs 41. Lugs 41 are secured to flange 35a by bolts 42 and nuts 43. 44 and 45 are brake shoes which are circular in contour and to the outer faces of which are secured brake linings 46, by means of rivets 47. The upper ends of brake shoes 44 and 45, Fig. 5, are hung on two pins 48 which are threaded and screwed into side frame 16. To the lower end of brake shoe 45 is pivoted an oil cylinder 49 by means of pin 50 and to the lower end of brake shoe 44 is pivoted the outer end of piston rod 51 by means of pin 52. To the inner end of piston rod 51, Fig. 5, is secured a piston 53 sliding freely in oil cylinder 49. To the open end of cylinder 49 is secured a cover 54 provided with proper packing and gland 55.

In the lower ends of side frames 15—16 is supported a shaft 56 on which is rotatively mounted an idler drum 57. 58 is a spacer and 59 is a bell crank. 59 comprises a hub 60 and levers 61 and 62. The lever 62 is forked and carries a roller 63 rotatively mounted on a pin 64.

Welded to the lower flanges 11a and 12a of the channel members 11 and 12, Figs. 2, 3, 4 and 5, is a heavy steel plate 65. Threaded into this plate are two upwardly projecting rods 66 and 67. The top end portions of rods 66 and 67 are threaded, as at 68, to receive two sets of nuts 69 and 70. Between the nuts 69 and 70 is securely clamped a yoke bar 71 to which is secured an oil cylinder 72, Fig. 5. In oil cylinder 72 slides a piston 73 provided with a piston rod 74 the lower end of which is threaded as shown at 75 and tightly screwed into an upper brake shoe 76. To the open end of cylinder 72 is screwed a cover 72a, provided with proper packing and gland 72b. Brake shoe 76 is provided with holes 77 to enable it to slide freely on rods 66 and 67. Running lengthwise on the underside of brake shoe 76 is a semi-circular groove 78 which is machined or provided in casting with a helical contour to fit over the strands of a twisted wire track cable 79. Resting on plate 65 is a lower brake shoe 79 provided with holes to assemble freely on rods 66 and 67. The top surface of this brake shoe 79 is provided with a longitudinal groove 80 machined or cast to fit the contour of the twisted wire track cable 79.

Near the end of channels 11 and 12 shown at the left in Figs. 2 and 3 is mounted a governor represented in its entirety by reference numeral 81. Governor 81 consists of a bracket or frame 82 secured to the journal 20 as by cap screws 83. In bracket 82, Fig. 5, is rotatively mounted a shaft 84 to the lower end of which is keyed the bevel gear 24 by means of key 24a. To the upper end of shaft 24 is secured the sleeve 85 by means of pin 85a. The upper end of sleeve 85 is provided with two upwardly extending forked brackets 86. Between the fork ends of the brackets 86 two gear segments 87 are rotatively mounted on pins 88.

Gear segments 87 are provided with rigidly connected arms 89 to the lower end of which are attached governor balls 90. Meshing with gear segments 87 are rack teeth 91 which are an integral part of shaft 92. Shaft 92 is free to slide in sleeve 85. Through the lower end of shaft 92 is pressed a pin 93 which is free to slide in elongated apertures 94 of sleeve 85. The outer ends of pin 93 support a sleeve 95 which is provided with an annular groove 96 into which is rotatively mounted a split ring 97. Pivoted at 99 on each half of the split ring 97 are the end portions of a forked lever 100 which is part of a bell crank 101. 102 is the other lever of bell crank 101.

Bell crank 101 is supported from the channel 75

12 by means of a bracket 103 bolted to the channel 12 by bolts 104, Fig. 3. To the lower end of lever 102 is pivoted a connecting link 105 by means of pin 106. The other end of the link 105 is connected to the outer end of a valve stem 107 by means of a pin 108.

The four way valve of which valve stem 107 is a part is shown in longitudinal section in Fig. 6 and is represented in its entirety by reference numeral 109. Valve 109 consists of a body portion 110 having a bore 111 to receive pistons 112 and 113, which can be an integral part of valve stem 107. The body 110 is provided with an inlet port 114 and with outlet port means 115 and 116 uniting in a common outlet 117. The body 110 is also provided with two discharge ports 118 and 119. The arrangement of the ports 114, 115, 116, 118 and 119 and the spacing of the pistons 112 and 113 is such that when oil is admitted into port 114, the pistons 112 and 113 being to the extreme left as shown by broken lines in Fig. 6, the oil will flow from port 114 into the discharge port 118 and the returning oil will discharge by way of ports 119 and 115 into and through final exhaust port 117. When the pistons are toward the right, as shown in full lines in Fig. 6, the oil will flow from port 114 into discharge port 119 and the returning oil will discharge into port 118 and finally into exhaust port 117. Into the ends of body 110 are screwed heads 120 and 121 provided with packing 122 and glands 123 and 124.

Connected to port 119 of valve 109 is one end of a pipe 125 the other end of which connects to the lower end of oil cylinder 72, Fig. 5. From pipe 127 branches off another pipe 126 which connects to the right end of oil cylinder 49. To port 118 connects a pipe 127 which branches off into two pipes 128 and 129. Pipe 128 connects to upper end of oil cylinder 72 and pipe 129 connects to the left end of the oil cylinder 49.

From Fig. 6 it will be evident, the pistons being in position shown by full lines, the oil will pass through pipe 125 into the lower end of cylinder 72 releasing the cable clamping shoes 76 and 79 and oil will flow into pipe 126 and the right hand end of cylinder 49 setting the brake shoes 44 and 45 in the brake drum.

The right hand end of valve stem 107, Fig. 5, is connected to a loose connecting link 130. One end of loose connecting link 130 is drilled and provided with threads for receiving a threaded end portion 131 of the valve stem 107. The link 130 is provided with an elongated transverse aperture 132. The right end of link 130, Fig. 5, is provided with hole 133 connecting with the aperture 132. Sliding freely in aperture 132 is a cross head 134 into which is threaded a stem 135. To the opposite end of stem 135 is secured a piston 136 which is slidably disposed in a cylinder 137. Also slidably disposed in cylinder 137 is another piston 138 to which is connected a stem 139. Piston 138 is provided with a small hole 138a. The right end of cylinder 137, Fig. 5, is provided with a cover 140.

To the outer end of stem 139 is connected one end of a push-pull cable 141. The other and lower end of push-pull cable 141 is provided with a forked end piece 142 which is pivoted 70 to the lever 61 as shown at 143, Fig. 2. Push-pull cable 141 is guided in a tube 144 one end of which connects to cover 140 and the other end of which terminates in bracket 145 of side frame 16, Fig. 2.

Parts 130 to 140 inclusive constitute delayed

action means between the valve 109 and the push-pull rod 141. In this delayed action means the two pistons 136 and 138 in cylinder 137, the piston 138 having the bleeder hole 138a therein, form an air coupling which operates as follows: When tension is exerted on wire 141 the piston 138 will be moved to the right, Fig. 5. Because the hole 138a is small movement to the right, Fig. 5, of piston 138 will operate by suction to move piston 136 along with it, that is the piston 136 will be moved to the right by atmospheric pressure acting against the side thereof opposite to the piston 138. This will move the valves 112 and 113 to the right, Fig. 6, into the position in which they are shown by full lines. Also this movement of piston 136 will act through stem 135, link 130, stem 107, link 105, bell crank 101, sleeve 95 and shaft 92 to lift governor arms 89. A pull can be exerted on the push-pull cable 141 by the winding in of a pick-up cable 182 on the drum 29. This pick-up cable 182 carries a trip member 183 which engages the roller 63 when a load is raised, thereby moving the lever 62, 61 and exerting a pull on cable 141.

As soon as the pistons 138 and 136 have been moved to the right, Fig. 5, as just explained, air which has been compressed between piston 138 and the cover 140 of cylinder 137 will begin to pass through small opening 138a and will tend to return the piston 136 to its original position. The elongated slot 132 in link 130 makes possible this return movement of piston 136. As soon as this delayed action of the air coupling devices has taken place it is possible for the arms of the flyball governor to drop and in so doing to move the valve members 112 and 113 back to the left to the position in which they are shown by broken lines in Fig. 6. Weight of the roller 63 and lever arm 62 will act through the cable 141 to move the piston 138 to the left, Fig. 5, to its initial position after the roller 63 is released by trip member 183.

The push-pull cable 141 is part of a control means which is responsive to a winding in of the pick-up line 182 and this control means operates in conjunction with the control means which is responsive to movement and stoppage of the carriage relative to the track cable 171 without hampering the operation of the last mentioned control means.

Referring to Figures 3 and 5 reference numeral 146 indicates an oil pump in its entirety. This oil pump comprises a cylinder 147 near the closed end of which are provided a suction inlet port 148 and a discharge port 149. The suction inlet port 148 is provided with a spring loaded ball check valve 150 and the discharge port 149 is provided with a spring loaded ball check valve 151. The body 147 of the valve has a bore 152 to receive a closely fitted reciprocating piston 153. To the outer end of the reciprocating piston 153 is pivoted one end portion of a connecting link 154 as by a pivot 155. The other end portion of the connecting link 154 is bored out as shown at 156 to permit the eccentric 25 to rotate freely therein. The pump body 147 is provided with lugs 157 drilled to receive cap screws 158 by means of which the pump is secured to channel 11, see Fig. 3.

Between the upper cross channels 13 and 14 is provided an accumulator tank 159 secured in place by means of straps 160 attached to the channels by screws 162. Secured to channel 11 is a reservoir tank 163 held in place by straps 161.

The pump inlet check valve 150 is connected to

the reservoir 163 by means of pipe 164. Pump discharge check valve 151 is connected with one side of a by-pass valve 165 by means of pipe 166. The other side of the by-pass valve 165 is connected to the accumulator 159 by means of pipe 167. The by-pass valve 165 is connected with the reservoir 163 by means of a pipe 168.

The accumulator 159 is partly filled with air and the bypass valve is arranged in such a manner and set so that the oil will discharge from pump 146 through pipe 166 through valve 165 through pipe 167 into accumulator 159 until a predetermined pressure is reached after which time the oil will be by-passed by valve 165 into pipe 168 which leads to the reservoir 163.

The intake port 114 of the four way valve 109 is connected by means of pipe 169 with the accumulator tank 159 and the exhaust port 117 is connected by means of pipe 170 with reservoir 163.

Referring to Fig. 1, which is illustrative of one set-up in which this carriage can be used, the carriage 10 is supported on a track cable or skyline 171 which extends between spar-trees 172 and 173. A haul-in cable 174, herein referred to as a main line, is secured to the carriage 10 by winding it on one of the drums, such as drum 28, Fig. 3. This main line 174 extends in one direction from said carriage 10 and over a sheave 175 on the spar tree 173 and thence down to a drum 176 on a donkey engine 177. A haul-back line 178 is wound on another drum, such as the drum 30, of the carriage 10 and extends in the opposite direction from the main line 174 and over a sheave 179 on the spar tree 172 and thence back to a drum 180 on the donkey engine 177. Preferably the donkey engine 177 is positioned near the spar tree 173 toward which logs 181 are to be hauled. A pick-up line 182 is wound on the third drum 29 of the carriage 10 and extends downwardly therefrom over the guide roller 51, see also Fig. 2, for use in picking up a load such as a log 181. A combined stop and trip member 183 is secured to the pick-up line 182 near the outer end thereof for the purpose of engaging with the roller 63 and operating the push-pull cable 141 in tube 144, Figs. 2 and 5, when the pick-up line is wound in.

The operation of this load pick-up and transporting device is as follows: As a starting point it will be assumed that the carriage 10 is at rest on the track cable or skyline 171 at a station near the spar tree 173 where logs or other loads are to be delivered and that the pick-up line 182 is in a lowered position. Under these conditions the valve members 113 and 112 will be in the positions in which they are shown by broken lines in Fig. 6, the cable clamp will be tightly clamped onto the track cable 171 and the drum locking means or brake will be released. By pulling on the main-line 174 the pick-up line will be wound on the drum 29 until the trip member 183 thereon engages the roller 63 and exerts a pull on the member 141. This will move the valve members 112 and 113 to the right into the position in which they are shown by full lines in Fig. 6 thus reversing the hydraulic connections to the cylinders 72 and 49 so that the cable clamp will be released and the drum locking brake will be applied. Also the pull of the member 141 will act through stem 139, pistons 138 and 136, stem 135, valve stem 107, bell crank 101 and shaft 92 to lift the arms 89 of the fly ball governor 81. Next by winding in the haul-back line 178 and slackening the main line 174 the carriage 10 can be moved out along the track cable 171 to a po-

sition where a load is to be picked up. Movement of the carriage 10 along the track cable 171 will rotate the flyball governor 81 and keep the arms thereof raised. This will maintain the fluid pressure connections by which the cable clamp is held released and the drum locking means or brake is held set or applied. The trip member 183 will remain in engagement with the roller 63 until the drum locking means is released but the piston 136 and stem 135 of the air coupling means will move to the left, Fig. 5, so that the arms of the flyball governor can drop and move valves 112 and 113 to the left when the carriage 10 is brought to a stop. Thus when the carriage 10 is stopped on the track cable the arms of the flyball governor will drop and this will move the valve members 113 and 112, Fig. 6, back to the position in which they are shown by broken lines. This reverses the hydraulic connection through the four way 20 valve 109 so as to apply the cable clamp to the track cable 171 and release the drum locking means. With the drum 28, 29, 30 thus released and the carriage 10 held immovable on the track cable 171 the pick-up line 182 can be lowered by winding in the haul-back line 178 and slackening the main line 174. After a load such as a log 181 has been made fast to the pick-up line 182 this load can be lifted clear of the ground by winding in the main line 174 and slackening the 30 haul-back line 178. When the lug 183 on the pick-up line 182 engages the roller 57 movement will be transmitted through member 141, air coupling 136, 137, 138, stem 135 and valve stem 107 to move the valves 112 and 113 to the right, Fig. 6, thereby releasing the cable clamp and applying the drum locking means. This allows the load to be hauled in by winding in the main line 174 and slackening the haul-back line 178. While the load is being hauled in the fly ball governor will maintain the correct position of the valves 112 and 113 and the air coupling piston 136 and stem 135 will be moved back to the position in which they are shown in Fig. 5 so that when the carriage is stopped at the unloading station the 40 arms of the governor 81 can drop and reverse connections through the valve 109. This clamps the carriage 10 to the track cable 171 and releases the drum locking means and permits the load to be lowered by slackening the main line.

The pump 146 is driven from the shaft 21 and, for this reason, is responsive to movement of the carriage 10 on the track cable 171 and is further responsive to stoppage of said carriage on said track cable. As the fly ball governor 81 is driven from the same shaft 21 the movements of the flyball governor 81 and pump 146 are synchronized. For this reason it is possible to replace the flyball governor by fluid pressure operated control means which is responsive to the operation and stopping of the pump.

Such a control means is illustrated in Fig. 7, and comprises a tubular body member 184 having therein a cylindrical chamber 185 positioned between two other chambers 186 and 187. A piston 188 is reciprocably disposed within the cylindrical chamber 185 and has a small perforation 188a provided therein. Two piston rods 189 and 190 are integral with or otherwise rigidly secured to the piston 188 and are supported and guided in suitable bearing members 191 and 192 which are connected with the respective end portions of the body member 184. Suitable packing means 193 is provided in connection with each bearing member 191 and 192.

The body member 184 is fixedly attached to any suitable part of the frame of carriage 10. The rod 190 is connected as by bracket means 194 with the link 105, or said rod 190 can be connected directly with the stem 107 of valve 109. The chamber 186 is connected with the discharge outlet of the pump 146. This can be done by detaching conduit 166 from pump 146 and bypass valve 165 and connecting one end portion of a conduit or pipe 195 with the chamber 186 and the other end portion of said conduit 195 with the check valve 151 at the pump outlet.

The chamber 187 is connected with the accumulator tank 159 as by connecting one end portion of a conduit 197 with said chamber 187 and the other end portion of the conduit 197 with the by-pass valve 165 in place of the detached conduit 166. This places the control member of Fig. 7 in a fluid conduit line between pump 146 and the by-pass valve 165.

A spring 198 is provided to urge the piston 188 to the left as shown in Fig. 7.

The operation of the control device shown in Fig. 7 is as follows: When the carriage is at rest on the track cable 171 the pump will be stopped and the spring 198 will move the piston 188 the maximum distance to the left, Fig. 7. This will position the valves 112 and 113 as shown by broken lines in Fig. 6 thereby setting the cable clamp and releasing the drum brake. When the trip member 183 on the pick-up line engages the roller 63 and exerts a pull on the push-pull cable 141 the valves 112 and 113, Fig. 6, and the piston 188, Fig. 7, will all be moved to the right thereby releasing the cable clamp and setting the drum brake. This makes it possible to move the carriage 10 along the track cable and operate the pump. Liquid from the pump entering the chamber 186 and flowing past the periphery of the piston to the chamber 187 on its way to the accumulator tank 159 will hold the piston to the right, Fig. 7, as long as the pump continues to operate. When the pump is stopped by the stopping of the carriage the spring 198 will move the piston 188 to the left as fast as the liquid escaping through perforation 188a will permit thus setting or applying the cable clamp and releasing the drum brake.

In some instances it may be desired to use the 50 haul-back line 178 to pull the outer end of the pick-up line 182 out to where loads are to be picked up. When this is to be done the haul-back line can be disconnected from the drum means 27 and connected directly with the pick-up line 182, preferably outwardly from the trip member 183. Also when this is to be done the haul-back line 178 is passed around any number of sheaves required to guide it to a position near where the load is to be picked up. Consequently for this mode of operation it is necessary either to detach and move the sheave 179 away from the spar tree 172 or to disconnect the haul-back line from this sheave 179 and pass said haul-back line over one or more other sheaves 55 located at a distance from the spar tree 172. These sheaves can be positioned to one side of the sky line 171 and near the ground and at a location which will make it possible to use the haul-back line 178 to move the carriage out along the sky-line 171 and to unwind and pull out the pick-up line 182.

When the carriage is thus used with the haul-back line 178 connected directly with the pick-up line 182 only two of the three drums 28, 29, 30 are used and for this mode of operation it would

be possible to dispense with one drum in the construction of this carriage.

From the above it will be seen that the essential requirements of the drum means 27 are that this drum means be of a suitable construction so that a main line, such as the line 174 and a pick-up line, such as the line 182 can both be wound thereon, the drum means being constructed and arranged so that when one of these lines is drawn out the other line will be wound in the vice versa. Obviously the construction of the drum means can be varied as long as two drum members are interconnected in such a manner as to accomplish this purpose.

The foregoing description and accompanying drawings clearly disclose a preferred embodiment of this invention but it will be understood that this disclosure is merely illustrative and that changes in the invention may be made within the scope and spirit of the following claims.

I claim:

1. Load pick-up and transporting devices comprising an overhead track cable; a carriage mounted to travel thereon; cable clamp means carried by the carriage operable to grip the cable and support the carriage immovable on the track cable; and fluid pressure devices carried on the carriage and responsive to movement and stoppage of said carriage relative to said track cable and connected with said cable clamp means for operating the same.

2. Load pick-up and transporting devices comprising an overhead track cable; a carriage mounted to travel thereon; cable clamp means carried by the carriage operable to grip the cable and support the carriage immovable on the track cable; fluid pressure operated cable clamp applying and releasing devices connected with said cable clamp means for operating the same; fluid pressure storage means mounted on said carriage; and fluid compressing means carried by said carriage and operable by the carriage in response to movement of said carriage along said track cable for compressing fluid in the fluid pressure storage means to operate said fluid pressure devices.

3. Load pick-up and transporting devices comprising an overhead track cable; a carriage mounted to travel thereon; cable clamp means carried by the carriage operable to grip the cable and support the carriage immovable on the track cable; fluid pressure operated cable clamp applying and releasing devices connected with said cable clamp means for operating the same; a storage receptacle for fluid under pressure carried by said carriage and communicatively connected with said fluid pressure operated cable clamp applying and releasing devices; pump means carried by said carriage adapted to supply fluid under pressure to said storage receptacle; and devices operated by the carriage in response to movement of said carriage along said track cable for driving said pump means.

4. Load pick-up and transporting devices comprising an overhead track cable; a carriage mounted to travel thereon; cable clamp means carried by the carriage operable to grip the track cable and support the carriage immovable on the track cable; fluid pressure supply means carried by said carriage; fluid pressure operated devices communicating with said supply means and connected with said cable clamp means, whereby the cable clamp means can be applied to and released from the track cable; and control devices responsive to movement and stop-

ping of said carriage relative to said track cable controlling said fluid pressure operated devices, whereby said fluid pressure operated devices are actuated to apply said cable clamp means and hold the same applied when the carriage is at rest on the track cable and to hold said cable clamp means released when the carriage is being moved along the track cable.

5. Load pick-up and transporting devices comprising an overhead track cable, a carriage having sheaves adapted to run on said track cable; cable clamp means carried by said carriage operable to grip the cable and support the carriage immovable on said track cable; a fluid pressure accumulator tank carried by said carriage; a pump carried by said carriage and communicatively connected with said tank; pump driving means connecting said pump with a sheave of said carriage for driving the pump by movement of the carriage along said track cable; and fluid pressure actuated clamp operating means communicatively connected with accumulator tank and operatively connected with said cable clamp means.

6. Load pick-up and transporting devices comprising an overhead track cable; a carriage having sheaves adapted to run on said track cable; cable clamp means carried by said carriage operable to trip the track cable and support the carriage immovable thereon; a fluid pressure accumulator tank carried by said carriage; a pump carried by said carriage and communicatively connected with said tank; pump driving means connecting said pump with a sheave of said carriage for driving the pump by movement of the carriage along the track cable; fluid pressure operated devices communicating with said accumulator tank and connected with said cable clamp means for applying and releasing said cable clamp means; and control devices responsive to movement of said carriage along said track cable adapted to supply fluid under pressure to said fluid pressure operated devices and apply said cable clamp means to said track cable when movement of said carriage on said track cable ceases.

7. Load pick-up and transporting devices comprising an overhead track cable; a carriage movable on said track cable; a plurality of interconnected winding drums carried by said carriage; drum locking means operable to lock and release said winding drums; a main line wound on one of said winding drums; a pick-up line wound on another of said winding drums; and a haul-back line wound on one of said drums operable to unwind the pick-up line when said drum locking means is released and to move the carriage outwardly along the track cable when said drum locking means is set to lock said winding drums.

8. Load pick-up and transporting devices comprising an overhead track cable; a carriage movable on said track cable; a plurality of rigidly connected coaxial winding drums carried by said carriage and adapted respectively to have a main line, a haul-back line and a pick-up wound thereon; drum locking devices operable to lock said drums against rotation; and fluid pressure operated control means responsive to movement of said carriage on said track cable adapted to apply said drum locking devices and lock said drums against rotation in response to movement of said carriage on said track cable.

9. Load pick-up and transporting devices comprising an overhead track cable; a carriage

11

mounted to travel on said track cable; cable clamp means carried by said carriage operable to grip said track cable and support said carriage immovable on said track cable; three rigidly connected coaxial winding drums carried by said carriage and adapted respectively to have a main line, a haul-back line and a pick-up line wound thereon; drum locking devices operable to lock said drums against rotation; and fluid pressure operated control means responsive to movement of said carriage on said track cable adapted to apply said cable clamp and release said drum locking devices in response to stoppage of movement of said carriage on said track cable.

10. Load pick-up transporting devices comprising an overhead track cable; a carriage mounted to travel on said track cable; cable clamp means carried by said carriage operable to grip said track cable and hold said carriage immovable on said track cable; a winding drum carried by said carriage and adapted to have a pick-up line wound thereon; drum locking devices operable to lock said drum against rotation; means operable to rotate said winding drum; and fluid pressure operated control means responsive to movement of said carriage along said track cable operable to hold said cable clamp released and said drum locking devices in drum locking position in response to movement of said carriage along said track cable and operable to apply said cable clamp and release said drum locking devices in response to stoppage of movement of said carriage on said track cable.

11. Load pick-up and transporting devices comprising an overhead track cable; a carriage movable on said track cable; cable clamp means carried by said carriage operable to grip said track cable and hold said carriage immovable on said track cable; three rigidly connected coaxial winding drums carried by said carriage and adapted respectively to have a main line, a haul-back line and a pick-up line wound thereon; drum locking devices operable to lock said drums against rotation; and fluid pressure operated control means responsive to movement of said carriage along said track cable operable to hold said cable clamp released and said drum locking devices in drum locking position in response to movement of said carriage along said track cable and operable to apply said cable clamp and release said drum locking devices in response to stoppage of movement of said carriage on said track cable.

12. Load pick-up and transporting devices comprising an overhead track cable; a carriage adapted to run on said track cable; cable clamp means carried by said carriage operable to grip the track cable and support the carriage immovable on the track cable; a fluid pressure accumulator tank carried by said carriage; fluid pressure supply means carried by said carriage and communicatively connected with said tank; three rigidly connected coaxial winding drums carried by said carriage and adapted respectively to have a main line, a haul-back line and a pick-up line wound thereon; drum locking devices operable to lock said drums against rotation; fluid pressure operated devices communicating with said accumulator tank and connected with said cable clamp means for applying and releasing said cable clamp means; other fluid pressure operated devices communicating with said accumulator tank and connected with said drum locking devices; and control means controlling the supply of fluid under pressure to both of said fluid pressure operated devices, said control means being responsive to movement of said carriage along said track cable whereby said cable clamp will be held released and said drum locking devices will be held locked when said carriage is moving along said track cable and said cable clamp will be applied and said drum locking devices released when movement of said carriage on said track cable is stopped.

12

both of said fluid pressure operated devices, said control means being responsive to movement of said carriage along said track cable whereby said cable clamp will be held released and said drum locking devices will be held locked when said carriage is moving along said track cable and said cable clamp will be applied and said drum locking devices released when movement of said carriage on said track cable is stopped.

13. Load pick-up and transporting devices comprising an overhead track cable; a carriage having sheaves adapted to run on said track cable; cable clamp means carried by said carriage operable to grip the track cable and support the carriage immovable thereon; a fluid pressure accumulator tank carried by said carriage; a pump carried by said carriage and communicatively connected with said tank; pump driving means connecting said pump with a sheave of said carriage for driving the pump by movement of the carriage along the track cable; three rigidly connected coaxial winding drums carried by said carriage and adapted respectively to have a main line, a haul-back line and a pick-up line wound thereon; drum locking devices operable to lock said drums against rotation; fluid pressure operated devices communicating with said accumulator tank and connected with said cable clamp means for applying and releasing said cable clamp means; other fluid pressure operated devices communicating with said accumulator tank and connected with said drum locking devices; and control means controlling the supply of fluid under pressure to both of said fluid pressure operated devices, said control means being responsive to movement of said carriage along said track cable whereby said cable clamp will be held released and said drum locking devices will be held locked when said carriage is moving along said track cable and said cable clamp will be applied and said drum locking devices released when movement of said carriage on said track cable is stopped.

14. Load pick-up and transporting devices comprising an overhead track cable; a carriage having sheaves adapted to run on said track cable; cable clamp means carried by said carriage operable to grip the track cable and support the carriage immovable on said track cable; a winding drum carried by the carriage and adapted to have a pick-up line wound thereon; drum locking devices operable to lock said drum against rotation; means operable to rotate said winding drum; control means responsive to movement of said carriage along said track cable operable to hold said cable clamp released and said drum locking devices in drum locking position in response to movement of said carriage along said track cable and to apply said cable clamp and release said drum locking devices in response to stoppage of movement of said carriage on said track cable; and means operated by winding in said pick-up line for initially operating said control means to release said clamp means and apply said drum locking means when said pick-up line is wound up to a load carrying position on said drum.

15. The apparatus as claimed in claim 14 in which the means operated by winding in the pick-up line comprises a push-pull cable connected by air coupling devices with the control means, said air coupling devices comprising two separate pistons operable in a cylinder in close contact with the cylinder walls, whereby a suction connection between said two pistons is pro-

vided, at least one of said pistons having an air passageway of small size extending from one side to the other thereof for slow relief of suction between said pistons thereby providing delayed action release between the push-pull cable and the control means.

16. Load pick-up and transporting devices comprising an overhead track cable; a carriage mounted to travel thereon; cable clamp means carried by the carriage operable to grip the track cable and support the carriage immovable on the track cable; a hydraulic cylinder connected with the cable clamp means for applying and releasing the same; a fluid pressure accumulator tank carried by the carriage; fluid pressure supply means carried by the carriage and connected with said tank and operated by movement of the carriage along the track cable; a winding drum carried by the carriage adapted to have a pick-up line wound thereon; brake devices operable to lock said drum against rotation; a hydraulic cylinder connected with said brake devices operable to apply and release the same; conduit means connecting both of said hydraulic cylinders with said tank; a four way valve in said conduit means; and control devices connected with said four way valve and responsive to movement of said carriage along said track cable, said control devices operating to hold said cable clamp released and said drum brake set in response to movement of said carriage along said track cable and being operable to apply said cable clamp and release said drum brake in response to stoppage of movement of said carriage on said track cable.

17. Load pick-up and transporting devices comprising an overhead track cable; a carriage mounted to travel thereon; cable clamp means carried by the carriage operable to grip the track

cable and support the carriage immovable on the track cable; fluid pressure operated devices mounted on the carriage connected with the cable clamp means for applying and releasing the same; and fly ball governor means mounted on the carriage operated by the carriage in response to movement of the carriage along the track cable and controlling said fluid pressure operated devices.

18. Load pick-up and transporting devices comprising an overhead track cable; a carriage mounted to travel on said track cable; cable clamp means carried by said carriage operable to grip the track cable and support the carriage immovable on the track cable; hydraulic means mounted on the carriage operable to apply and release the cable clamp; a pump carried by the carriage and connected with said hydraulic means and operated by the carriage in response to movement of the carriage along the track cable; a valve mounted on said carriage controlling the intake and discharge of liquid as respects said hydraulic means; and control devices for said valve mounted on said carriage and operated by the pressure of fluid discharging from said pump.
